UNITED STATES PATENT OFFICE.

CHARLES T. BRADY, OF DETROIT, MICHIGAN.

DESIGN FOR A PARLOR LAMP.

Application filed November 11, 1926. Serial No. 19,668. Term of patent 14 years.

To all whom it may concern:

Be it known that I, CHARLES T. BRADY, a citizen of the United States, residing at Detroit, in the county of Wayne and State of Michigan, have invented a new, original, and ornamental Design for Parlor Lamps, of which the following is a specification, reference being had to the accompanying drawing, forming part thereof.

The figure is a perspective view of the parlor lamp showing my new design.

I claim:—

The ornamental design for a parlor lamp, as shown.

CHARLES T. BRADY.
